UNITED STATES PATENT OFFICE.

EUGENE L. McGARY, OF CHICAGO, ILLINOIS.

CONTROLLING MECHANISM FOR HYDRAULIC PRESSES.

1,283,837.

Specification of Letters Patent.

Patented Nov. 5, 1918.

Application filed May 17, 1917. Serial No. 189,269.

To all whom it may concern:

Be it known that I, EUGENE L. McGARY, a citizen of the United States, and a resident of Chicago, in the county of Cook and State 5 of Illinois, have invented certain new and useful Improvements in Controlling Mechanism for Hydraulic Presses, of which the following is a full, clear, and exact description.

10 The invention relates to controlling mechanism for hydraulic presses and similar machines.

In practice, it has been found, particularly where hydraulic operated machines are operated under high pressure, as a matter of economy, to employ a fluid under a lower pressure to operate the tool or ram during the idle portions of the stroke or during those portions of the stroke when the high 20 pressure is not necessary for the work. In the operation of these machines with fluids of different pressures, when under manual control, extreme care must be taken to prevent the sudden application of high pressure, because of the danger of breaking parts 25 of the machine or the work and of injury to the machine resulting from sudden application of the high pressure. In many cases, the operators of the machines are paid by 30 piece work and there is a tendency to prematurely apply the high pressure to save time, and this has been found to be detrimental to the machine and tools operated thereby.

35 It has been sought, in practice, to meet these problems by initially choking the high pressure fluid supply, but this has been found to be objectionable because of the loss of time, particularly in certain work, such as rubber vulcanizing, where, at times, the full unrestricted flow of high pressure is 40 desired. In other instances, it has been sought to meet these problems in practice by a series of cumulatively opening ports which 45 are successively uncovered as the piston travels its cycle. In these mechanisms, the valves are required to travel over leather or similar packings which rapidly wear out and are of doubtful dependency and involve 50 complications which preclude quick repair or adjustment.

A primary object of the present invention is to provide improved controlling means which is automatic in its operation, so that 55 the operator, after starting the machine with low pressure, can leave the machine and at-

tend to other work and in which the maximum low pressure first opens a small valve or port to cause the pressure in the machine to be gradually increased until the full flow 60 of high pressure may be safely applied to the machine.

A further object of the invention is to attain this result by a construction in which there is metal-to-metal engagement between 65 the valve and its seat so that the high pressure will not rapidly wear or cut away the valve or its seat.

By providing an improved controlling mechanism in which the operator manually 70 controls the supply of low pressure fluid to the machine, then supplying a choked or restricted flow of high pressure fluid to the machine when the predetermined maximum of low pressure has been reached and then 75 causing the increased pressure to subsequently, automatically open a valve which permits the full flow of high pressure fluid into the machine, it has been found that 80 danger of breakage or injury to the machine or work is effectively prevented and the control is automatic so that the operator, after starting the machine, can leave it and attend to other work.

Another object of the invention is to provide 85 an automatic controlling device of this type which may be readily attached or applied to machines of usual construction.

Another object of the invention is to provide improved mechanism of this type by 90 which the high and low pressures are successively controlled automatically by valves which are constructed for metal-to-metal contact surfaces.

The invention consists in the several novel 95 features hereinafter set forth and more particularly defined by claims at the conclusion hereof.

In the drawings: Figure 1 is an elevation of a hydraulic press equipped with the invention. Fig. 2 is a section of one form of controlling mechanism embodying the invention. Fig. 3 is a section of another form of the invention. Fig. 4 is a section of another form of the invention.

The invention is shown as applied to a hydraulic machine comprising a suitable frame 5, a working cylinder 6 adapted to receive fluid under pressure, a platen 7 adapted to be operated by a piston in the cylinder, and 110 a coöoperating stationary member 8 supported by the frame 5. It will be under-

stood that the invention is adapted to be applied to any machine adapted to be operated by fluid under pressure.

- A pipe 9 is connected to deliver fluid 5 under pressure into the cylinder from a casing 10 of a suitable main or manually controlled operating valve 11 which controls the supply of low pressure fluid to the pipe 9. Low pressure fluid is conducted to the casing 10 by a pipe 12 containing a check valve 14 which prevents the fluid from being forced backwardly through the low pressure supply. An exhaust pipe 15 is connected to the casing 10 so that when the valve 11 is operated to cut off the supply of fluid, the fluid will exhaust from the working cylinder 6 through pipe 9, casing 10 and pipe 15.
- The automatic controlling mechanism, as exemplified in Figs. 1 and 4, comprises a 20 casing 17 to which is connected a high pressure supply pipe 18 and a pipe 19 which is connected to the pipe 9. Pipe 19, in this exemplification of the invention, serves to conduct low pressure fluid from the pipe 9 or the press connection, which is in communication with the working cylinder 6, to the casing 17 to operate the high-pressure controlling mechanism and also serves to conduct high pressure fluid from the casing 17 25 to the pipe 9 and the working cylinder at proper times. A chamber 21 in the casing 17 constantly receives high pressure fluid from pipe 18 and a chamber 22 is in communication with the chamber 21 by a small port 23, a wear-nozzle 24 being provided at the point where the duct connects with the chamber 21. A valve 20 controls the flow of high pressure fluid through a duct 25 to pipe 19. This duct is of sufficient size to 30 permit the maximum or full flow of high pressure fluid. Valve 20 is normally closed against a metal seat 26 formed in the casing 17 and is provided with an upper stem 27 which is guided in a removable plug 28, a 35 suitable packing 29 being provided below the plug to prevent leakage of the fluid. The valve 20 is formed with a shoulder 30 upon which the fluid in the chamber 21 acts to aid in holding the valve normally closed. The 40 valve 20 is also provided with a lower stem 31 which extends through and is guided in a removable plug 33. Suitable packing 34 is provided at the upper end of the plug 33 to prevent leakage of the fluid. A spring 35 bears against the plug 33 and its lower 45 end engages a socket 36 which is adjustably held on the stem 31 by a nut 37. This construction permits adjustment of the spring 35 to vary the pressure required to open the 50 high pressure valve 20 so that the controlling mechanism can be adjusted for different work without dismantling the mechanism. The upper end of stem 27 is accessible so it can be held while nut 37 is being adjusted.
- 65 A small by-pass port 38 connects cham-

ber 22 and the duct 25 and the upper end of this duct is provided with a valve seat for a gradual flow valve 39 which is normally closed and is guided in a plug 40 which is removably secured to the casing 17. Packing 41 is provided at the lower end of plug 40 to prevent the leakage of fluid. A spring 42 is mounted in a socket in the upper portion of plug 40 and is applied to hold the valve 39 closed. A cap 43 is screw-threaded to the upper end of plug 40. A set screw 44 is adjustably held in said cap and serves as an adjustable abutment for the upper end of the spring. A lock nut 45 holds screw 44 in its assigned position. By adjusting screw 44, the pressure required to overcome spring 42 and open the valve 39 may be varied as desired for different work.

The operation of the construction thus far described will be as follows: When the ram 7 is to be operated, the operator will manipulate the valve 11 which may be of any suitable construction, to cause low pressure fluid to flow from pipe 12 through casing 10 and pipe 9 into the working cylinder 6. 90 Normally, valves 39 and 20 are closed and will remain so until the maximum of the low pressure fluid has been reached. When that occurs, the pressure of the fluid in duct 38 against the lower end of valve 39 will be 95 sufficient to open said valve and thereupon a small volume of high pressure fluid will flow from chamber 21 through nozzle 24 port 23, chamber 22 and port 38 to duct 25 and gradually increase the pressure in the 100 pipe 9 and the working cylinder. During this operation, the check-valve 14 will prevent the back-flow of fluid into the low pressure pipe. When the pressure has been gradually increased to a point where substantially the full flow of high pressure fluid may be applied without danger either to the work or to the machine, the pressure of the fluid in duct 25 acting against the underside of valve 20 will be sufficient to open said 110 valve against the force of spring 35 and the fluid pressure upon the top of shoulder 30. Thereupon, the high pressure fluid in full volume will continue to flow directly from chamber 21 to duct 25 and through pipe 115 9 to the working cylinder. As long as the valve 11 is allowed to remain open, the full high-pressure will be applied to the ram and work which is a desideratum in some work. The operator, after opening the valve 120 11, can leave the machine to attend to other work, because the subsequent control is automatic, until the operation has been completed. When it is desired to release the work, the operator will shift the valve 11 125 to open the exhaust 15. As soon as there is material drop in pressure in the chamber 25, the valve 39 will be closed by a spring 42 and valve 20 will be closed by spring 35. When the fluid has been exhausted 130

from cylinder 6, the machine will be ready for another operation. Any time it may be desired to vary the points at which the valves 39 and 20 shall open responsively to 5 fluid pressures, it is only necessary to adjust the springs to hold said valves closed, which can be done while the machine is in operation.

In Fig. 2, there is shown an exemplification 10 of the invention in which both the low pressure and the high pressure fluids flow through the casing of the controlling-mechanism. In this form of the invention, the pipe 9^a leads from the valve casing 10 and 15 is connected to the casing 17^a. A pipe 9^b connects said casing and the cylinder 6. Both of these pipes communicate with a chamber 46 in casing 17^a. Low pressure fluid will flow from pipe 9^a through chamber 20 46 and pipe 9^b to the cylinder under control of the valve 11. A hollow plug or sleeve 47 of wear-metal is secured in casing 17^a and the full flow-valve 30^a for the high-pressure fluid engages a seat in the upper 25 end of sleeve 47. The stem 30^a of valve 30^a is guided in a hollow plug 48 which is secured to the casing 17^a. Packing 49 is provided around the lower end of the stem 30^a and a spring 50 engaging the adjustable 30 stop and guide 51 serves to press valve 30^a into its closed position. A lock nut 52 holds the member 51 against rotation in plug 48. The pressure exerted by this spring may be varied as desired. A port 53 is formed vertically 35 through the sleeve 47 and a valve seat 54 is formed at the lower end of said sleeve which is engaged by a gradual flow valve 55 which is normally closed and is adapted to be operated by fluid under pressure in the port 53. The stem of valve 55 is guided in a hollow plug 56 containing a spring 57 for holding the valve normally closed. The stem of valve 55 works through the packing 58. The force of spring 57 40 may be adjusted by a member 59 which is screw-threaded to the lower end of plug 56. A high pressure supply pipe 60 is connected to casing 17^a to deliver fluid into a chamber 61. A small port 62 in sleeve 47, connects 45 chamber 46 and duct 53 to supply fluid for opening valve 55 for gradual delivery of high pressure fluid through port 62 and chamber 46 and pipe 9^a to the press. In this form of the invention, the valve 11 50 controls the supply of low pressure fluid to the cylinder and chamber 46. When the low pressure fluid reaches a predetermined maximum in chamber 46, duct 62 and port 53, it will act upon the upper end of valve 55 and force it open against the force of 55 spring 57, whereupon the high pressure fluid from pipe 60 will flow gradually through the port 62 into the press connection and cylinder 6. After the pressure has 60 gradually increased to the point when it is

safe to admit full flow of high pressure, without danger to the press or work, the pressure of fluid against the underside of valve 30^a and against the shoulder 30^b on stem 30 will be sufficient to open valve 30^a against 70 the force of spring 50, whereupon the full flow of high pressure fluid will pass from duct 53 directly into chamber 46 and thence to the press connection. This form of the invention exemplifies one in which both 75 high-pressure and low pressure pipes are connected to the casing of the controlling mechanism.

In the form of the invention illustrated in Fig. 3, the pipe 9^c from the press connection 80 pipe 9 (Fig. 1) is connected to the casing 17^b of the automatic controlling mechanism. The high pressure pipe 18^a is connected to said casing to deliver fluid into a chamber 61. A full-flow valve 62 operates against 85 a seat 63 and is held normally closed by a spring 64. The stem 65 of valve 62 is provided with a packing 66 held by a follower 67 and nut 68 to prevent leakage of fluid from the chamber in which the stem works. 90 An adjusting screw 69 serves to vary the pressure of spring 64 as desired. This screw is supported in a plate 70 suspended from casing 17^b by rods 71 and nuts 72. The stem of valve 62 extends upwardly 95 from the valve and has connected thereto a sleeve 73 which is slidably mounted in a guide ring 74 and packing 75. A gradual-flow valve 76 for the high pressure fluid is mounted to work in the stem of the full 100 flow valve and to control the flow of high pressure fluid through a small by-pass port 77 formed in said stem and through which a small volume of high pressure fluid can flow from chamber 61 into the press connection 105 when valve 76 is open. A spring 78 is applied to hold valve 76 normally closed. This spring is mounted in a member 79 secured to the upper end of sleeve 73, a packing 80 being provided to prevent leakage of fluid around the stem of valve 76. 110 An adjusting screw 81 is provided for spring 78. Both the adjusting screws 81 and 69 are accessible from the outside of the casing so that the points at which the gradual and full flow valves will be operated 115 may be varied as desired.

In the operation of the form of the invention shown in Fig. 3, pipe 9^c will initially receive low pressure fluid from the 120 press connection under control of valve 11 (Fig. 1). When the low pressure fluid has reached the point when it is safe to gradually admit high pressure fluid, the fluid in the press connection, acting through port 125 77, will exert sufficient pressure on the lower end of the gradual-flow valve 76 to overcome the force of spring 78 and open said valve, whereupon high pressure fluid from chamber 61 will flow through port 77 and 130

gradually increase the pressure in the press. The stem 65 is provided with a shoulder 65' and the exposed area of said shoulder and the packing 66 is greater than the area 5 of the valve stem and parts moving therethrough which is exposed to counter-pressure of the fluid in the chamber 61, so that when the pressure in chamber 61 has increased sufficiently to act on said shoulder 10 65' and packing 66 to overcome the force of spring 64, as the result of the gradual flow of high pressure through port 77, the full-flow valve 62 will be opened and thereafter the high pressure will flow directly 15 from chamber 61 to the press. When the fluid is exhausted from the press connection the spring 64 will promptly close valve 62 and spring 78 will quickly close the low pressure connection. This form of the invention exemplifies one in which the gradual flow valve is slidably mounted in the 20 stem of the full flow valve.

The invention thus exemplifies an improved automatic controlling mechanism 25 for hydraulic machines or presses in which the operator manually controls the flow of the low pressure fluid and in which there is a gradual-flow valve for delivering high pressure fluid to the press connection and a 30 full-flow valve controlled by the fluid under pressure so that the full flow of the high pressure fluid may be maintained as long as desired. Also one in which the pressures at which the gradual flow and full flow of 35 the high pressure fluid may be quickly varied to adapt the controlling mechanism for different work without dismantling the controlling mechanism.

The invention is not to be understood as 40 restricted to the details set forth, since these may be modified within the scope of the appended claims, without departing from the spirit and scope of the invention.

Having thus described the invention, what 45 I claim as new and desire to secure by Letters Patent, is:

1. In controlling mechanism for fluid pressure operated machines, the combination of a supply for high pressure fluid, a supply 50 for low pressure fluid, means for controlling the supply of low pressure fluid to the machine and automatic controlling mechanism comprising a gradual flow valve operable by low-pressure fluid, and a separately operating automatic full-flow valve 55 both of said valves being connected to the same high pressure supply and to control the flow of said high pressure fluid from said supply to the machine.

60 2. In controlling mechanism for fluid pressure operated machines, the combination of a supply for high pressure fluid, a supply 65 for low pressure fluid, means for controlling the supply of low pressure fluid to the machine and automatic controlling

mechanism comprising a gradual flow valve operable by low pressure fluid and a separately operating full flow valve operable only by fluid of greater pressure than the low-pressure fluid, both of said valves being connected to the same high pressure supply and to control the flow of said high pressure fluid from said supply to the machine. 70

3. In controlling mechanism for fluid 75 pressure operated machines, the combination with a hydraulic press, of a supply for high pressure fluid, a supply for low pressure fluid, a check-valve in the low-pressure supply, means for manually controlling the supply of low pressure fluid to the machine and automatic controlling mechanism comprising a gradual flow valve operable by low pressure fluid and an automatic separately operating full flow valve, both of said valves 80 being connected to the same high pressure supply and to control the flow of said high pressure fluid from said supply to the machine. 85

4. In controlling mechanism for fluid 90 pressure operated machines, the combination of a supply for high pressure fluid, a supply for low pressure fluid to the machine, automatic controlling mechanism comprising a gradual-flow valve operable 95 by low pressure fluid and an automatic separately operating full-flow valve, both of said valves being connected to the same high pressure supply and to control the flow of said high pressure fluid from said supply to the 100 machine, and means for varying the operation of said valves so they will be opened at different pressures.

5. In controlling mechanism for fluid 105 pressure operated machines, the combination of a supply for high pressure fluid, a supply for low pressure fluid, means for controlling the supply of low pressure fluid to the machine, automatic controlling mechanism comprising a gradual flow valve operable by low pressure fluid and a separately operating full flow valve operable by 110 fluid pressure, both of said valves being connected to the same high pressure supply and to control the flow of said high pressure fluid from said supply to the machine, and means accessible from the outside of said mechanism, for varying the operation of said valves so they will be opened at different pressures. 115

6. In controlling mechanism for fluid 120 pressure operated machines, the combination of a supply for fluid under low pressure, a supply for fluid under high pressure, a manually operable valve for controlling the flow of low pressure to the press, a full-flow valve for the supply of high pressure to the machine, and means in virtue of which said full-flow valve is operable only by a predetermined pressure of fluid in ex- 125 130

- cess of the maximum working force of the low pressure fluid supplied to the machine, and when the working force of the low pressure fluid has been supplemented by fluid from the supply of high pressure controlled by the full flow valve.
7. In controlling mechanism for fluid pressure operated machines, the combination of a supply for fluid under low pressure, a supply for fluid under high pressure, a manually operable valve for controlling the flow of low pressure to the machine, an automatic gradual flow valve operable by low-pressure fluid, for controlling the supply of high pressure to the machine, a full-flow valve, and means in virtue of which said full-flow valve is operable only by a predetermined pressure of fluid in excess of the maximum working force of the low pressure fluid supplied to the machine, and when the working force of the low pressure fluid has been supplemented by fluid from the supply of high pressure controlled by the full flow valve.
8. In controlling mechanism for fluid pressure operated machines, the combination of a supply for fluid under low pressure, a supply for fluid under high pressure, a manually operable valve for controlling the flow of low pressure to the machine, an automatic gradual-flow valve operable by

low pressure fluid for the supply of high pressure to the machine, a full-flow valve, and means in virtue of which said full-flow valve is operable only by a predetermined pressure of fluid in excess of the maximum of the low pressure fluid supplied to the machine, and means whereby the pressure at which the gradual and full-flow valve will open may be varied from the outside.

9. In controlling mechanism for fluid pressure operated machines, the combination of a supply for high pressure fluid, a supply for low pressure fluid, means for manually controlling the supply of low pressure fluid to the machine and controlling mechanism comprising a casing, a connection for delivering low pressure fluid to the casing, said high pressure supply being connected to deliver fluid to said casing, a gradual-flow valve operating in the casing and operable by low pressure fluid to control the gradual flow of high pressure fluid to the press connection, a full flow valve for the high pressure fluid in the casing, and means in virtue of which said full-flow valve is operable by fluid in the press connection after the fluid has been delivered thereto through the increase of pressure from the gradual flow of high pressure fluid.

EUGENE L. McGARY.
